UNITED STATES PATENT OFFICE.

SHERMAN CLEMINSHAW, OF TROY, NEW YORK, AND BENJ. W. RANDALL,
OF MADISON, NEW JERSEY.

SIPHON.

SPECIFICATION forming part of Letters Patent No. 224,149, dated February 3, 1880.

Application filed July 7, 1879.

To all whom it may concern:

Be it known that we, SHERMAN CLEMINSHAW, of the city of Troy, county of Rensselaer, and State of New York, and BENJAMIN WILEY RANDALL, of Madison, in the county of Morris, and in the State of New Jersey, have invented certain new and useful Improvements in Siphons; and we do hereby declare that the following is a full, clear, and exact description 5 thereof, reference being had to the accompanying drawing, and to the letters of reference marked thereon, making a part of this specification.

Our invention relates to siphons; and it consists in the construction of a device whereby a suction may be created to obviate sucking by the mouth, as will be hereinafter more fully set forth.

In order to enable others skilled in the art 20 to which our invention appertains to make and use the same, we will now proceed to describe its construction and operation, referring to the annexed drawing, which represents a longitudinal section of our invention.

25 A represents the barrel or body of the suction-tube, provided with screw-caps B B' on its ends. C is a hollow piston passing through the cap B, and provided on its inner end with a follower, D. The cap B' has a tubular projection, B², on which the pipe E is fastened.

a is a valve in the end of the barrel. d is a valve in the handle or pulling-piece F, screwed on the outer end of the piston. e is a spring for holding the valve d to its seat. b is a 35 guide for the stem of said valve, and f is a stop to prevent said valve from opening too far.

The pipe E may be a rubber hose, or made of metal or other material, and when attached to the tubular projection B' its other end is then placed in the liquid to be drawn.

40 The hand-piece F being grasped by the operator and drawn down, the valve a opens, and on the piston being pushed back closes and the valve d opens, thus producing a suction or partial vacuum, and the atmospheric pressure, acting upon the liquid with a vacuum below the valve a, causes the liquid to flow and open both valves, so that the liquid will find free egress out through the hollow piston. Now, 45 by pushing the plunger back while the stream is running, a shut-off is obtained by the end of the plunger coming against and closing the valve a, thus enabling the operator to control the flow of the liquid at will, or by partially closing it to reduce the size of the stream.

50 Having thus fully described our invention, what we claim as new, and desire to secure by Letters Patent, is—

55 The combination of the barrel A, having screw-caps B B', the pipe E and handle F, 60 the hollow piston C, with follower D, valves a d, spring e, guide b, and stop f, all constructed and arranged to operate substantially as and for the purposes herein set forth.

In testimony that we claim the foregoing 65 we have hereunto set our hands and seals this 1st day of July, 1879.

SHERMAN CLEMINSHAW. [L. S.]
BENJAMIN WILEY RANDALL. [L. S.]
